CEMENTING AND FLOATING SHOE FOR
WELL CASINGSClarence E. Burt, Los Angeles, Calif., assignor
to Baker Oil Tools, Inc., Huntington Park,
Calif., a corporation of California

Application June 25, 1930, Serial No. 463,662

2 Claims. (Cl. 166—1)

This invention relates to well cementing devices and apparatus.

Hitherto a cementing device has been produced which included a casing shoe having a cementitious plug cast therein. This cementitious plug is formed with a central valve chamber from the opposite ends of which extends a comparatively small passageway through both the upper and lower ends of the plug. A ball valve is arranged 10 in this chamber, which valve is buoyant in fluid cement and is adapted to cooperate with a valve seat at the upper end of the valve chamber so as to prevent the passage of fluid upwardly through the plug. Means are provided, however, 15 for preventing the ball valve from obstructing the flow of fluid through the lower end of the plug from the valve chamber.

This prior device when used for cementing was maintained off the bottom of the well in order that 20 the cement could discharge through the lower passage and force itself upwardly around the shoe. In some instances, however, it is desirable to supplement this lower passage with passageways extending from the valve chamber outwardly 25 through the sides of the shoe.

It is the principal object of the present invention to provide a device of the character referred 30 to wherein outlet passageways are provided which extend radially from the valve chamber and terminating at their outer ends in helical nozzles so 35 designed that the ejected cement will be forced in an upward helical path and substantially tangentially to the outer periphery of the shoe.

In carrying this object into practice radial passageways are formed from the valve chamber 35 through the plug and the outer surface of the shoe is formed with upwardly directed helical slots directed substantially tangential to the outer periphery of the shoe. Baffle means cooperate 40 with these slots so that the ejected cement will flow in a helical path around the shoe and tangential to the surface thereof. The advantage of this is to prevent an undesirable washing action 45 on the sides of the hole and also to provide even distribution of the cement around the shoe and to prevent channeling of the cement.

One form which the invention may assume is exemplified in the following description and illustrated by way of example in the accompanying 50 drawing, in which:

Fig. 1 is a vertical transverse section through a shoe embodying the preferred form of my invention.

Fig. 2 is a side elevation of the same.

Fig. 3 is a partial side elevation.

Fig. 4 is a transverse section taken on line IV—IV of Fig. 2.

Fig. 5 is a fragmentary view in transverse section taken through one of the slots in line V—V of Fig. 2.

Referring more particularly to the accompanying drawing, in Fig. 1 I have illustrated a casing shoe 10 which is cylindrical and within which a cementitious plug 11 is cast. Grooves 12 are formed in the interior surface of the shoe 10 so 10 that interlocking connections may be formed between the plug 11 and the casing shoe so as to prevent dislodgment of the plug by pressure applied to either end thereof.

Formed in the plug is a valve chamber 14, the 15 upper end of which is defined by a flat disc 15 preferably of bakelite or other similar non-metallic but friable material. The lower end of the chamber 14 is defined by a concave disc 16 which is likewise formed of bakelite or similar 20 material. Extending between these discs 15 and 16 is a cylinder 17, also formed of non-metallic material, the ends of which project into grooves formed in the adjacent surfaces of the discs 15 and 16. It will be noticed that the peripheral 25 edges of the discs 15 and 16 extend beyond the outer peripheral surface of the cylinder 17 and are anchored within the cementitious body portion of the plug 11.

An upper passageway 18 is formed coaxially 30 of the plug and extends between the valve chamber 14 and the space interiorly of the shoe above the plug. A valve seat 19 is formed at the lower end of the passageway 18. A similar passageway 20 is formed in the plug from the lower end of the 35 valve chamber through the lower end of the plug. This passageway is, as illustrated, in alignment with the passageway 18. A ball valve 21 is disposed in the valve chamber 14 for cooperation 40 with the valve seat 19. This ball valve 21 is in reality a back pressure valve and is preferably buoyant in such fluid as hydraulic cement, so that when the pressure enters into the valve chamber 14 from the passageway 20 the ball valve 21 will rise and seat on the seat 19 and prevent the passage of fluid upwardly through 45 the passageway 18.

Extending radially from the valve chamber 14 is a plurality of radial passageways 22. These 50 passageways extend radially outwardly and are directed slightly upwardly. In the present instance I have illustrated four of these radial passageways spaced at equal distances apart. The inner ends of these radial passageways 22 55

communicate with the interior of the valve chamber 14. The outer ends of the passageways communicate with nozzles 23 formed in the shoe 10. These nozzles 23 comprise substantially helical slots 24 formed in the shoe 10. These slots are arranged on an angle of substantially forty-five degrees to a vertical line parallel to the axis of the shoe. Each slot 24 communicates at its lower end with a port 25 formed completely through the shoe in alignment with the adjacent radial passageway 22.

It will be noticed that the bottom of the slots are formed tangential to the exterior surface of the shoe. Between the outer surface of the shoe 15 and the bottom of the slots, the sides of each slot is grooved to receive a baffle plate 26 which lies parallel to the bottom of the slot at a spaced distance therefrom over the port 25 and extends to a point a short distance above the port 25 as 20 illustrated in Fig. 2. These baffle plates 26 are preferably secured in place in such a manner that they will not become dislodged after the device is assembled.

It will therefore be seen that a nozzle which 25 is helically and upwardly directed and which is substantially tangent to the shoe 10 is formed in the shoe at the end of each of the radial passageways 22. Therefore, cement ejected from the passageways 22 through the nozzles 23 will be caused to travel in a path which is both helical 30 and tangent with respect to the shoe. This will insure distribution of the cement around the shoe and also prevent channeling of the cement.

When the device is in operation cement is 35 forced downwardly unseating the ball valve 21 and causing the cement to eject radially outwardly through the passageways 22 and through the nozzles 23. If circulation is established through the passageway 20 cement will also eject 40 through this passageway. However, if circulation is not established through this lower passageway a perfect cementing job will be insured through the medium of the passageways 22 and the nozzles 23.

The forming of the nozzles 23 prevents an undesirable washing action on the walls of the hole and also insures even distribution of the cement around the shoe.

Although I have illustrated and described the 50 device as a cementing shoe, the invention may be applied equally as well to a float collar; that is, the cementitious plug may be cast in a coupling interposed between sections of well casing as well

as in a casing shoe which is fitted at the lower end of the well casing.

While I have shown the preferred form of my invention, it is to be understood that various changes may be made by those skilled in the art without departing from the spirit of the invention as defined in the appended claims.

Having thus described my invention, what I claim and desire to secure by Letters Patent is:

1. A cementing device of the character described including a cylindrical member, a substantially solid plug of cementitious material formed therein, said plug having a valve chamber formed therein and communicating with the interior of the cylindrical member above the plug, 15 valve means in said chamber for preventing the flow of fluid upwardly through said chamber into said cylindrical member above the plug, a plurality of radial passageways formed in said plug and extending from said valve chamber to the 20 inner periphery of said cylindrical member, a nozzle formed in the cylindrical member for each passageway, each of said nozzles including a port formed through the cylindrical member in communication with the adjacent radial passageway, 25 a groove extending upwardly and helically from the port with its bottom disposed on a tangent to the outer periphery of the shoe, and baffle means disposed over the port and having its inner surface spaced from the bottom of the groove to direct fluid emanating from port upwardly through the groove, said plug being also provided with upper and lower vertically aligned passageways extending from the chamber to the 30 top and bottom of the plug and forming a 35 straight opening through the plug.

2. A cementing device for well casings comprising a tubular cylindrical member adapted to be connected to the well casing, a plurality of nozzles formed in said cylindrical member, each 40 of said nozzles including a port formed radially through the cylindrical member, a groove formed in the outer surface of said cylindrical member extending upwardly and helically from the port with its bottom disposed on a tangent to the outer 45 periphery of said member, and a stationary baffle means for each nozzle, the same being disposed over the port and partly over the groove and secured to said member and having its inner surface spaced from the bottom of the groove to 50 direct fluid emanating from the port upwardly through the groove.
